United States Patent Office.

CHARLES FRANK, OF CINCINNATI, OHIO.

Letters Patent No. 71,293, dated November 26, 1867.

IMPROVEMENT IN TANNING.

The Schedule referred to in these Letters Patent and making part of the same.

TO ALL WHOM IT MAY CONCERN:

Be it known that I, CHARLES FRANK, of Cincinnati, Hamilton county, Ohio, have invented a new and useful Tanning Process, and do hereby declare the following to be a full, clear, and exact description of the same.

My process of tanning is essentially such as described in the patent of United States, numbered 52,655, except that in place of the turpentine there described I use the same quantity of hydrocarbon oil of any customary kind, such as coal oil, petroleum, naphtha, or benzine, or in some cases I use half the quantity of turpentine to that stated in the aforesaid patent, and an equal quantity of hydrocarbon.

When turpentine is used, any form of it will serve, but the form called Venice turpentine is believed the best.

I claim herein as new, and of my invention—

The tanning process or operation, substantially as described.

In testimony of which invention I hereunto set my hand.

CHARLES FRANK.

Witnesses:

GEO. H. KNIGHT,

JAMES H. LAYMAN.
